J. P. PEARCE,
BURGLAR ALARM,
APPLICATION FILED FEB. 11, 1914.

1,112,088.

Patented Sept. 29, 1914.

UNITED STATES PATENT OFFICE.

JOHN P. PEARCE, OF ALBERTVILLE, ALABAMA.

BURGLAR-ALARM.

1,112,088.

Specification of Letters Patent. Patented Sept. 29, 1914.

Application filed February 11, 1914. Serial No. 818,098.

To all whom it may concern:

Be it known that I, JOHN P. PEARCE, a citizen of the United States, residing at Albertville, in the county of Marshall and State of Alabama, have invented certain new and useful Improvements in Burglar-Alarms, of which the following is a specification, reference being had to the accompanying drawings.

10 This invention comprehends certain new and useful improvements in alarms and relates more specifically to burglar alarms.

An object of the invention is to provide a device of this character which may be connected with a door or window fastener to be operated to give the signal upon operation of the fastener.

Another object is to provide a device of this character which will be of extremely simple construction and operation and the operative parts of which may be normally held under tension and released for operation to sound the alarm upon operation of the door or window with which the alarm is connected.

Another object is to provide a device of this character which may be locked against operation by a slidable member connected with a rotary member of the door or window fastener, whereby upon rotation of said member, the slidable member will be operated to release the alarm mechanism and allow the latter to operate to give the desired signal.

35 A further object is to generally improve and simplify the construction and operation of devices of this character and increase the efficiency of the same, without materially increasing the cost of manufacture thereof.

40 With the above and other objects in view, my invention consists in certain novel constructions, combinations, and arrangements of parts to be hereinafter more fully described, claimed, and illustrated in the accompanying drawings, in which,

Figure 1 is a front elevational view, partly in section, showing the construction and application of my burglar alarm; Fig. 2 is a side elevational view of the alarm applied, 50 the casing for the operative parts being shown in section; Fig. 3 is a detail view partly in section, of a portion of the alarm.

55 Referring more specifically to the drawings in which similar reference characters designate corresponding parts throughout the several views, 1 designates the main

shaft of my apparatus to which is connected, one end of a spring 2, the opposite end of said spring being connected with the casing 3.

The casing 3 may be secured to a door or window and one end of the shaft 1 projects through the casing and has the key 4 upon its projected end, by means of which the shaft may be rotated to wind the spring 2. The shaft 1 also has the ratchet wheel 5 mounted thereon within the casing 3 and the shaft 1 is normally held against rotation by engagement of the inner enlarged or turned end 6 of the slidable rod 7 which is slidably engaged through the casing 3 and the bracket arm 8 within said casing 3. The outer end of the rod 7 is loosely connected with the connecting link 9 which is also connected with the knob carrying bar 10 of a door lock or fastener or to any other rotatable member of the door lock or fastener, as will be readily understood. It will therefore be seen that rotation of the member 10 in one direction, will cause the link to exert a pull on the dog and thus release it from engagement with the ratchet wheel, the movement of the rotatable member in the opposite direction causing the dog and link to have a sliding movement relative to each other, thus to prevent the dog from being moved into engagement with the ratchet wheel during its rotation and thereby prevent injury to its teeth. The shaft 1 also has an escapement wheel 11 mounted thereon and upon rotation of said shaft 1, the teeth of

the escapement wheel will engage successively with the opposite escapement pawls 12 secured to the cross bar 13 which is mounted intermediate its ends upon the fulcrum 14, whereby said cross bar 13 will be rocked upon the fulcrum pin, as the shaft 1 and escapement wheel 11 rotate and the teeth of said escapement wheel force outwardly, first one of the pawls and then the other, thereby oscillating the hammer arm 15 rigidly connected with the cross bar 13 and extending at right angles therefrom. The hammer arm 15 projects through the elongated slot 16 in the casing 3 and has the hammer 17 mounted upon its free end for engagement with the gong 18 upon rocking movement of the cross bar 13 to give the signal.

From the foregoing, it will be clearly apparent that I have provided a burglar alarm which may be readily applied to a door, window, or the like, and connected with the

mechanism employed for locking the door or window in closed position, whereby an alarm will be given upon operation of the locking mechanism previous to opening of the door or window. It will also be clearly apparent that this form of alarm may be wound and set, as desired, and locked against operation until the fastening mechanism for the door or window with which the alarm is connected, is operated to allow rotation of the main shaft of the alarm mechanism under tension of the spring secured thereto.

While I have shown the preferred embodiment of my invention, it will be understood that minor changes in the details of construction and arrangement of parts may be made within the scope of the appended claims without departing from the spirit of my invention or sacrificing any of the advantages of the same.

What is claimed is:—

In a burglar alarm, the combination with a gong and a hammer mechanism coacting therewith and including an anchor, of means

for actuating the hammer embodying a spring actuated shaft, a ratchet wheel and a crown wheel carried by the shaft, the latter being engaged by the anchor, a slidable dog normally engaging the ratchet wheel; a rotatable dog releasing member, and a link loosely connecting the dog and the rotatable member whereby turning of the latter in one direction will cause the link to exert a pull on the dog and thus release it from engagement with the ratchet wheel, the movement of the rotatable member in the opposite direction causing the dog and link to have a sliding movement relative to each other, thus to prevent the dog from being moved into engagement with the ratchet wheel during its rotation and thereby prevent injury to its teeth.

In testimony whereof I hereunto affix my signature in the presence of two witnesses.

JOHN + P. PEARCE.
